CLAIM

The ornamental design for a path light, as shown and described.

DESCRIPTION

FIG. 1 is a front, right, bottom perspective view of a path light;

FIG. 2 is a back, right perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines depict portions of the path light that form no part of the claimed design. The dot-dashed broken lines represent boundaries of the claimed path light and form no part of the claimed design.

1 Claim, 8 Drawing Sheets
